Company, a corporation of Ohio

Application January 8, 1935, Serial No. 876. Re-
newed June 22, 1938. In Great Britain July 24,
1933

12 Claims. (Cl. 209—496)

This invention relates to a jig, and more particularly to a jig used for washing coal and separating the clean coal from the refuse found intermingled therewith in the raw coal.

5 An object of the invention is to provide a jig with an improved fluid control means for adjustably directing the jiggling fluid through the jig screen to compensate for varying conditions encountered in practice.

10 Another object of the invention is to provide a multiple compartment jig in which each compartment has an individual refuse collector and elevator, whereby the refuse from each compartment may be separately received and, if desired, given individual treatment.

15 Another object of the invention is to provide a multiple compartment jig, the fluid pulsating means of which are operated in synchronism and at adjustable phase relations.

20 Another object of the invention is to provide an improved refuse chute which will relieve the discharge valve under abnormal conditions.

Still another object of the invention is to provide an improved refuse accumulation responsive 25 refuse discharge valve operating means for a jig.

25 Another object of the invention is to provide a jig including a perforate screen which is pivoted at one end adjacent a refuse discharge opening and adjustably mounted adjacent an opposite end whereby the rate of travel of the material across said screen may be adjusted.

30 Other objects of the invention will appear hereinafter, the novel features and combinations being set forth in the appended claims.

35 Referring to the drawings:

Fig. 1 is an elevational view of a three-compartment jig incorporating the features of our invention, two compartments of which are shown in longitudinal section, and parts of which are removed to show other details.

40 Fig. 2 is a transverse sectional view of the device of Fig. 1;

Fig. 3 is an enlarged detail, parts being shown in section, showing particularly the adjustable fluid directing plate;

45 Fig. 3a is a sectional detail taken on line 3a—3a of Fig. 3.

Fig. 4 is an enlarged elevational detail, showing parts of the float controlled refuse discharge mechanism;

50 Fig. 5 is an enlarged plan view of the mechanism of Fig. 4;

Fig. 6 is a sectional view on line 6—6 of Fig. 4;

55 Fig. 7 is an enlarged elevational view of the

float operated pawl and ratchet control mechanism for the refuse discharge valve;

Fig. 8 is a sectional view on the line 8—8 of Fig. 7;

Fig. 9 is an enlarged elevational view of the 5 details of the pawl mechanism of Figs. 7 and 8;

Fig. 10 is an enlarged detailed elevational view 10 of a valve and an adjustable eccentric mechanism which may be employed as a part of our invention:

Fig. 11 is a sectional elevational view of the device of Fig. 10; and

Fig. 12 is a sectional view of the eccentric mechanism of Figs. 10 and 11 taken on the line 15 12—12 of Fig. 10.

This application is a continuation in part of our application entitled Apparatus for treating mineral materials, Serial No. 736,442, filed July 23, 1934.

20 Referring particularly to the drawings, there is illustrated in Figs. 1 and 2 a jig including the features of our invention. As illustrated, this device comprises a multiple compartment jig and in the illustration given there are three compartments though, of course, this number may be 25 either increased or reduced, as desired. Broadly stated, the device comprises a lower frame structure 10, built up of longitudinal, lateral and upright channel members with cross angle members to increase the rigidity thereof. Within the 30 said lower frame 10 is supported an elongated tank 11 which is divided into three compartments 12, 13 and 14.

An upper frame 15 is also provided which is 35 rigidly attached to said lower frame 10, said upper frame being adapted to support the operating mechanism for each of the said jig compartments 12, 13 and 14. Said upper frame 15 includes a centrally disposed platform 16 upon which is mounted a speed reduction mechanism 40 18 driven from a motor 17 through a U-belt drive 19 (Fig. 2).

Extending longitudinally of said upper frame 15 is a pair of shafts 20 and 21, each of which is 45 driven from said speed reduction mechanism 18. Said shaft 20 carries a plurality of eccentrics, three in number, for operating air control valves, two of which are individual to the compartment 12 and one of which is individual to the compartment 13. Shaft 21 is also provided with 50 three eccentrics for driving individual air control valves, one of which is individual to compartment 13 and two of which are individual to compartment 14. In addition, the shaft 20 drives the elevator mechanism 22 individual to the 55

compartment 12. The shaft 21 also drives elevator mechanisms 23 and 24 individual to compartments 13 and 14, respectively. Said shaft 21 also drives the shaft 25 through chain and sprocket mechanisms 26 and 27, which shaft 25 is common to a plurality of refuse discharge devices, one for each of the compartments 12, 13 and 14.

The tank 11 is provided with a material receiving chute 28 which is adapted to receive the raw material to be treated by the jiggling device—as, for example, raw coal as received from the mine—and, with a treated material discharge chute 29 over which the treated material, such as clean coal, is adapted to be discharged into a receptacle or conveyor.

As the structural details of each of the several compartments 12, 13 and 14 are substantially the same, a description of one will suffice for all. Each of said compartments comprises an individual wash tank 30 having substantially parallel side walls 31 and 32 and an arcuate bottom wall 33. Extending longitudinally of the wash tank 30 and substantially parallel with the side wall 31 is a partition 33' which divides the wash tank 30 into a wash chamber 34 and an air chamber 35. Extending laterally between the partition 33' and the side wall 32, and thus within the wash chamber 34, is a material supporting screen or perforate plate 36. Adjacent one end of said screen 36 is a laterally extending weir 37 which is made of a pair of relatively adjustable plates and which is vertically adjustable by having elongated slots cooperating with nuts 37' which extend from a laterally extending plate, which plate is connected at its opposite ends to said partition 33' and side wall 32. The bottom edge of weir 37 is positioned above the lower and discharge end of said screen 36 to form an opening 38 of variable size of a refuse discharge chute 39 formed by upper and lower stationary walls 35' and 36' and a pivoted member 160, hereinafter described more in detail. A refuse discharge valve 40, of the rotary locking gate type, cooperates with said discharge chute 39 to discharge the refuse which accumulates on the screen 36, said refuse being discharged into the boot 41 of the elevator mechanism 22, 23 or 24, where it may be lifted by the buckets 42 of said elevator mechanism and discharged from the discharge opening thereof. A perforated coal discharge chute 38' directs material from the weir 37 to the next compartment screen 36.

Substantially longitudinally and centrally spaced with respect to the inclined screen 36 and extending between the walls 31 and 32 of the wash tank 30 and positioned between the walls 31 and 33' of the air compartment 35 and forming one wall of said air compartment, is a partition 43. This partition 43, in each of the compartments 12, 13 and 14, is effective to divide said compartments 12, 13 and 14 into sub-compartments, each of which has an individual air chamber 35 and an individual air control valve 44.

It will thus be seen that in the device illustrated there are three compartments 12, 13 and 14, each of which has an inclined screen 36, a weir 37, a discharge chute 39, a discharge valve 40 and a refuse elevator mechanism, and that each of said compartments 12, 13 and 14 is divided into two sub-compartments, each sub-compartment of which has an individual air chamber 35 with an individual air control valve 44. It is thus manifest that there will be six air control valves 44 and six sub-compartments for the three com-

partments 12, 13 and 14, each sub-compartment being provided with an individual air chamber 35.

Each of the air valves 44 is controlled by an adjustable eccentric mechanism 45. There are therefore six of said adjustable eccentric mechanisms, three of which are operated from the shaft 20 and three of which are operated from the shaft 21, as aforesaid. The air control valve 44 and the adjustable eccentric mechanism 45 may well take the form of the devices of Figs. 10, 11 and 12 which are hereinafter described and which are disclosed in detail in the application of Byron M. Bird for a Method of jiggling, Serial No. 736,443, filed July 23, 1934, and in the application of Byron M. Bird and Frank H. Smith for a Valve, Serial No. 736,444, filed July 23, 1934.

Said eccentric mechanism 45 is of such form that it may be operatively connected to the shafts 20 or 21 to have any one of three angular positions which are 120 degrees out of phase. The keyways of each eccentric are preferably aligned on shafts 20 and 21. By employing the eccentric mechanism disclosed in said Figs. 10, 11 and 12 and hereinafter described, it is possible to operate each of the valves 44 in synchronism with the phase relation of any valve 120 degrees out of phase with any other valve. One particular mode of operation of said valves which has been found to be particularly useful and to reduce appreciably both the air and the energy required to operate the device, is to set each of the two valves 44 of each individual compartment 12, 13 and 14 in phase and to set each pair of valves individual to each of said compartments 12, 13 and 14, 120 degrees out of phase with each other 35 and pair of valves; that is, the valves 44, individual to compartment 12, would operate in phase; the valves 44, individual to compartment 13, would also operate in phase with each other but 120 degrees out of phase with the valves of said compartment 12; and the valves 44, individual to compartment 14, would operate in phase with each other and 120 degrees out of phase with the valves of each of the compartments 12 and 13. This particular setting of said valves is illustrated in Fig. 1 of the drawings.

Each of said valves 44 is operative to control periodically the admission of air under pressure to its individual air chamber 35 and to exhaust air from said air chamber. In addition, where the valves are the type disclosed in said Figs. 10, 11 and 12, they may be adjusted to seal the chambers 35 twice during each cycle of operation—once under conditions of initial atmospheric pressure in said chambers and again under conditions above initial atmospheric pressure in said chambers.

The source of air supply which is controlled by said valves 44 may comprise an air pump or blower 46 which is connected to a common air storage tank 47 by a conduit 48. Said air storage tank 47 is preferably of sufficient size that there is no substantial reduction of air pressure therein when any of the valves 44 are operated. Individual conduits 49 having therein individual manually controllable valves 50 lead from the air storage tank 47 to the individual valves 44.

Each of the sub-compartments of the compartments 12, 13 and 14 is provided with a source of water comprising a valve controlled supply line 51, which is supplied with water from a common water main 52. It is thus manifest that each of the sub-compartments of the compartments 12, 13 and 14 may be individually controlled, both as to the amount of water supplied thereto and the 75

amount of air supplied thereto and exhausted therefrom.

Cooperating with each of the compartments 12, 13 and 14 is a refuse responsive float controlled refuse discharge mechanism. Said mechanism comprises a float 53 which responds to the accumulation of refuse on the screen 36 to control the actuation of the refuse discharge valve 40, thereby to maintain the refuse on the said screen 36 at a predetermined level. The details of this mechanism are illustrated in Figs. 4 to 9, inclusive, and will be described hereinafter.

Adjacent the bottom of each of the wash tanks 30, positioned below what is commonly termed the hutch, is a longitudinally extending trough 54 within which operates a screw conveying mechanism 55 for conveying the accumulated hutch refuse through the small opening 56 in the boot 41 of the elevating mechanisms 22, 23 and 24 where said refuse may be withdrawn by said elevating mechanisms. Said screw conveying mechanism 55 is driven from the lower or foot shaft of the elevator mechanism 22, 23 or 24, which shaft extends beyond both walls of the boot 41 and has a squared extension on the left hand end, as viewed in Fig. 1, to receive an internally squared extension on the right hand end of the central hollow pipe 55'. The left hand end of said screw mechanism 55 in compartment 12 is clamped to a small stud shaft by a clamp 56' formed of two half cylinders, one half of which carries part of the spiral forming the screw mechanism 55. Appropriate bolts and nuts maintain the clamp 56' on the mentioned stud shaft and pipe 55'. The left hand end of said stud shaft is carried in the cover bearing 57' which is removably attached to the bottom of tank 30, as by nuts and bolts. This cover bearing not only supports the stud shaft and thereby supports the left hand end of the screw conveying mechanism 55, but also provides a removable cover which may be removed and allow removal of said screw conveying mechanism by longitudinal movement thereof.

The screw conveying mechanism of compartments 12, 13 and 14 is thus driven from the foot shaft of its elevator mechanism 22, 23 and 24, respectively. In addition, all of said screw conveying mechanisms 55 are connected through the couplings 56' of compartments 13 and 14 and the elevator foot shafts.

It is evident that the screw conveying mechanisms 55 of compartments 13 and 14 cannot be removed in the manner above described with respect to the mechanism 55 in compartment 12. There is an additional way in which said screw conveying mechanism 55 of said compartment 12 may be removed and this also applies to each of the other compartments. The partition 43 has a portion 40' cut away above the trough 54 which is normally covered by a removable plate 41'. By removing the split coupling 56', the shaft 55' can be moved to the left sufficiently to disengage the aforementioned squared extension on the right hand end thereof from the aforementioned squared extension on the stub shaft. When this is done, the conveyor mechanism 55 is free to move and, with plate 41' removed, it may be pulled through the trough 54 and opening 40' in one of the sub-compartments. By pivoting the screen 36 and moving it out of the way or by removing man-hole cover 73, the said mechanism 55 may be removed from the tank 30. The plate 41' is provided to allow of two separate and distinct adjustments in each of the compartments whereby an initial

adjustment of air and water may be used in the first half of the compartment and a final adjustment of air and water may be used in the second half of the compartment.

Adjacent the bottom of each of the boots 41 is a fine refuse flush valve 57 which provides for flushing of the said boots 41.

From the above description of the jig, it is evident that in the operation thereof the raw coal to be treated is fed at the material receiving chute 28 onto the screen 36 of the first compartment 12. Rotating shafts 20 and 21 operating through the eccentric mechanisms 45 operate the individual air control valves 44 to admit air to the air chamber 35 and exhaust air from said chambers periodically. By setting the eccentric mechanisms 45 of each of the compartments 12, 13 and 14, 120 degrees out of phase with each other, it is evident that only two valves 44 will be open at the same time and thus the amount of air drawn from the storage tank 47 at any time will not be excessive. This particular mode of air admission also results in what may be termed a wave motion of the jiggling fluid in the compartments 12, 13 and 14 as the fluid in each of said compartments 12, 13 and 14 will go through a cycle of operation which is 120 degrees out of phase with the cycle of operation of fluid in each other compartment.

The material being treated, which in the example given will be considered as raw coal, is first received on the screen 36 of the compartment 12 and there subjected to the periodic pulsations of fluid moving upwardly and downwardly with respect to the screen 36. This movement of fluid with respect to said material will be effective to stratify the component parts thereof according to specific gravities as is set forth in considerable detail in the above mentioned application of Byron M. Bird, Serial No. 736,443. Part of the fine refuse of said raw material will be drawn down through the screen 36 into the hutch of the wash tank 30 and accumulate in the trough 54 where it will be conveyed by the screw conveyor 55 to the boot 41 of the elevator mechanism 22. As the said material is stratified on the screen 36, the heavy particles of refuse thereof, particularly the shale, will accumulate in the lower strata of the bed of materials with the components of intermediate specific gravity, such as bone or boney coal, in the intermediate strata and the clean coal in the top strata thereof. The first compartment 12 is preferably so adjusted as to be particularly effective to remove the shale and permit all of the clean coal and most of the bone or boney coal to pass over the weir 37 onto screen 36 of the second compartment 13.

The weirs 37 of compartments 12 and 13 are preferably lower in height than the corresponding weir 37 of compartment 14. This permits the stratification of coal and bone taking place in the upper layers of compartments 12 and 13 to be continuous and to extend into compartment 14. This is an important feature of our invention and increases the capacity of the jig by delivering material to compartments 13 and 14 which is partially stratified due to the action of the preceding compartment or compartments. The chutes 38' of sections 13 and 14 are perforated and receive water from the front sub-sections of compartments 13 and 14, respectively, whereby the stratification of the preceding compartment is maintained continuous over the refuse discharge boots 41. It is thus evident that

the stratifying action is continuous and undisturbed throughout the entire jig. Moreover, the absence of any dropping of material from one compartment to the next avoids any disturbance 5 of the stratified condition of the bed.

The refuse responsive float mechanism 53 of the compartment 12 is therefore adjusted to respond to a large accumulation of heavy specific gravity material, such as shale, to operate the refuse discharge valve 40. The coal, bone and boney coal received by screen 36 in the second compartment 13 is subjected to another jiggling operation and this compartment is preferably so adjusted as to remove any shale which may have 10 passed over the weir 37 of compartment 12 and most of the components of intermediate specific gravity—that is, the bone or boney coal. Therefore, principally pure coal with some of the fractions of intermediate specific gravity material— 15 that is, bone or boney coal and, particularly, the lowest specific gravity components thereof—will pass over the weir 37 of compartment 13 onto screen in the final compartment 14. Compartment 14 will be adjusted to remove effectively 20 those remaining fractions of refuse and discharge from the discharge chute 28 only the clean coal.

It is evident that, as the particular separation to be performed by each of the compartments 12, 25 13 and 14 is not of identical material, it probably will require a different adjustment of the operating mechanisms for each of these compartments. A wide range of adjustments is therefore provided by the mechanism, comprising our invention. For example the air valves 44 of each of the sub-compartments of compartments 12, 13 and 14 may be given a separate and distinct adjustment, if desired. Likewise, the water supplied to each of said sub-compartments may be individually adjusted. In addition, the refuse withdrawal mechanism 46 for each of said compartments 12, 13 and 14 may be individually adjusted and this is particularly important as the amount of accumulated refuse on the screen 36 has an 30 important bearing upon the results obtained in any compartment. In addition, the height of weir 37 of each compartment may be individually adjusted. By providing the individual elevator mechanisms 22, 23 and 24 for each of the compartments 12, 13 and 14, respectively, the component parts of the refuse may be received at separate points and thereafter receive individual treatment. For example, it may be found that the refuse from the last compartment 14 includes 35 a secondary coal which may be sold as such or may be crushed and returned to the material receiving chute 28 to be subjected again, with a new charge of coal, to a jiggling operation.

In addition to the adjustments for providing 40 individual control for each of the compartments 12, 13 and 14, each of the sub-compartments thereof is provided with an individual pivoted fluid deflecting plate 58 which comprises a pivoted continuation of the partition 33' and which 45 may be adjusted to vary the flow of fluid upwardly through the screen 36. As best illustrated in Figs. 1 and 3 of the drawings, this plate is attached at its upper end to a pivot shaft 59 pivotally mounted in brackets 59' and attached at its 50 lower end by a bracket 60 to one end of the adjusting rod 61 which rod extends through a packing gland 62 in the side wall 32 of said wash tank 30. The packing gland 62 comprises a base portion 63 which is preferably welded to said side 55 plate 32 and has a conical aperture 64 through

which said rod 61 extends. A brass knuckle 65 is threaded to receive the threaded end 66 of the rod 61 and is adapted to be clamped in the conical aperture 64 of said base 63, as by a clamping plate 67 provided with a conical aperture 68 and removably attached to said base 63, as by machine screws 69. The head of the brass knuckle 65 is preferably flattened at 70 along opposite side faces thereof to receive a wrench or tool, whereby it may be turned to move the rod 61 inwardly 10 or outwardly of the wash tank 30 and thereby to adjust the position of the deflecting plate 58. Said plate 58 is also preferably provided adjacent each side edge with a wiping member 71, such as a rubber strip, which makes a wiping contact with 15 the adjacent wall of the sub-compartment. Said strip is attached to said plate 58 by clamping plate 71' and appropriate fastening means, as nuts and bolts.

It is thus seen that the partition 33', which divides the wash tank 30 into the wash chamber 34 and the air chamber 35, has a pivoted adjustably positionable extension for each of the sub-compartments of the compartments 12, 13 and 14 which may individually regulate the lines of flow 20 of jiggling fluid with respect to the screens 36. This pivoted extension is adjustable while the device is in operation due to the fact that the adjusting means therefor is accessible from the outside of the wash tank. To adjust said mechanism, machine screws 69 are sufficiently released to allow turning of the brass knuckle 70 and, when the adjustment is completed, said screws are drawn home and the knuckle 70 held in a fixed position to form a water-tight packing 35 gland.

In addition to the above mentioned elements, each of the compartments 12, 13 and 14 may be provided with longitudinally extending reinforcing pipes 72 which are rigidly attached at their 40 ends to the end walls of each of the wash tanks 30 and to the central partitions 43 thereof. Each of the compartments 12, 13 and 14 is also provided with a covered manhole 73, the cover of which may be removed to provide access to said compartments for making any repairs and for providing 45 access thereto for any other purpose.

Referring more particularly to Figs. 4, 4, 6, 7, 8 and 9 of the drawings, there is illustrated in detail the refuse accumulation responsive float 50 controlled refuse discharge mechanism which constitutes one feature of our invention. This device comprises a float 53, preferably stream lined by having a rounded front with side walls tapering to a point at the rear, as best indicated in Fig. 5, which may well take the form of a hollow aluminum member. Said float is provided with a pointer 74 adjacent the top thereof adapted to cooperate with a scale 75, which is mounted on bracket 76 carried on cross channel member 77 60 between the side wall 32 of the tank and the partition 33' thereof, to indicate the refuse depth. Said float 53 is carried upon a parallel motion mechanism comprising two pairs of lever arms 78 and 79 having heads 80 and 81, respectively, provided with a plurality of apertures 82 and 83, respectively, for receiving trunnion bolts 84 and 85, respectively, extending through said float 53. It is manifest that, by removing the cotter pins which are provided for each of said bolts 84 and 85 and removing said bolts from the float 53, said float may be adjusted to any desired position with respect to said lever arms 78 and 79 and retained in said adjusted position by re-inserting said bolts 84 and 85 and fastening the cotter pins. Said 70 75

lever arms 78 and 79 are pivoted, respectively, to the shafts 86 and 87 which are mounted on non-friction bearings in the journals 88 and 89, respectively, of the bracket 76. The lever arms 79 are removably attached to the shaft 87, as by clamping cap screws and cooperating washers 90. One of the lever arms 78 is removably attached to one end of the shaft 86, as by cap screw and washer 91, while the other lever arm 78 is attached to said shaft, as by a cotter pin 92.

While no particular attempt is made to attach the lever arms 79 rigidly to the shaft 87 so that said shaft 87 rotates responsive to the movement thereof, the lever arms 78 are keyed to said shaft 86, as by keys 93, to provide positive rotation of said shaft 86 responsive to movement of said lever arms 78, which movement is, of course, controlled by the float 53. The shaft 86 has an extension 94 over which is adapted to be slipped the hub 95 of a lever arm 96 carrying an adjustable counter-balancing weight 97 adapted to counter-balance the normal weight of the float mechanism 53. Said hub 95 also receives a reduced extension on a cross shaft 98 and is preferably rigidly attached thereto, as by welding. The hub 95, riding on extension 94, thereby provides one bearing support for said shaft 98. Integrally formed with said hub 95 is an extending arm 99 having a U-shaped end 100, the side flanges of which are adapted to extend adjacent the upper and lower edges of one of the lever arms 78, whereby said arm 99 will transmit the motion imparted to lever arms 78 by the float 53 to the cross shaft 98.

The other end of the cross shaft 98 is journaled in a bearing 101 mounted on a bracket 100' attached to the end of the cross channel 77. Rigidly attached to said cross shaft 98 to rotate therewith and extending rearwardly therefrom is a lever 102 provided with a plurality of apertures 103 adapted to receive selectively the bifurcated end of a coupling member 104 which is attached to a downwardly extending rod 105 which carries at its lower end an adjustable coupling 106 (Fig. 7) provided with an elongated aperture 107. Said coupling 106 is screw-threaded with the lower end of the shaft 105 and is provided with a lock nut 107' whereby said coupling may be adjustably positioned on said shaft 105 and whereby the end of said shaft 105 may be variably extended to restrict the amount of lost motion provided by said elongated aperture 107. It is thus seen that a mechanism is provided whereby the position of the float 53 may control the rod 105 which rod may, in turn, be employed to control the operation of the refuse discharge valve 40, the details of which will now be described.

Said refuse discharge valve 40 comprises a paddle wheel 108 which, as seen in Fig. 1, cooperates with the chute 39 to remove the refuse accumulated in said chute and discharge said refuse into the boot 41 of the elevator mechanisms 22, 23 and 24, respectively. Said paddle wheel 108 is mounted on the shaft 109 (Fig. 8) which extends through a mounting 110 comprising a removable plate 111 having a hub 112 which is provided with an enlarged recess adapted to receive felt washers 113 of a packing gland which washers may be compressed by compression bushing or gland 114 adapted to be adjusted by headless studs and cooperating nuts 115. The plate 111 is provided with a circumferential flange 116 adapted to be attached by cap screws 117 to a ring 118 rigidly secured to the side wall 32 of

the wash tanks, as by welding. A gasket 118 is preferably positioned between the flange 116 and ring 117 to provide a water-tight connection. It is to be noted that the internal diameter of the ring 117 is larger than the diameter of the paddle wheel 108 whereby, upon removal of the cap screws 117, the paddle wheel may be removed by being drawn outwardly through said ring 117.

Rigidly attached to the flange 116 is the base 119 of a bracket 120 which has a pair of spaced upstanding arms carrying spaced journal bearings 121 and 122 through which extend the outer end of the shaft 109. Said base 119 may be attached to said ring 117, as by cap screws 123' 15 which extend through said flange 116 and into said ring 117. The bearings 121 and 122 are provided with inner circumferential bearing surfaces 123 and 124, respectively, which cooperate with the outer portion of the shaft 109, and with 20 external bearing surfaces 125 and 126, respectively, for a purpose which will be hereinafter described.

The shaft 109 is provided at its outer end with a grease fitting 127 cooperating with an 25 axial drill hole 127' which communicates with circumferential grease grooves 128 to supply grease to said bearing surfaces 123 and 124, respectively. Adjacent said bearing surfaces 123 and 124, the bearings 121 and 122 may be provided with appropriate grease grooves 128' and 129.

A pair of levers 130 and 131 is provided with bearing rings 132 and 133, respectively, which cooperate with the inner portions of the bearing 35 surfaces 125 and 126, respectively, and are rotatable with respect thereto. Said rings 132 and 133 have extending arms 134 and 135, respectively, adapted to carry counter-weights 136 and 137, respectively, which may be adjusted on 40 said extending arms, as by clamp screws 138.

Intermediate the bearings 121 and 122 and keyed rigid with the shaft 109 is a ratchet wheel 139. It is thus evident that upon rotation of the ratchet wheel 139 the shaft 109 will be rotated with the paddle wheel 108 to effect the discharge of accumulated refuse in the chute 39.

To effect a rotation of said ratchet wheel 139, there is provided a pair of pawls 140 and 141 which are of unequal length and which are 50 mounted upon a bolt 142 extending between spaced bell crank levers 143 and 144 having bearing rings 145 and 146, respectively, cooperating with the outer extensions of the bearings 125 and 126, respectively.

Between the bearing rings 133 and 146 is a spacing washer 147. A similar spacing washer 148 is also positioned between the bearing rings 132 and 145. These washers are preferably provided with the rotation preventing tongues extending into slots 149 and 150, respectively, of said bearings 125 and 126. Arms 143' and 144' of the bell crank levers 143 and 144 are provided with extensions 151 and 152, respectively, having appropriate bearing rings adapted to receive the 60 trunnions of a cross head 152', which cross head is adapted to receive the end of a reciprocating rod 153 and to be adjustably attached thereto by spaced nuts and washer 154.

As best illustrated in Fig. 1, the rod 153 is continuously driven from an eccentric mechanism 154 driven from the shaft 25. As the shaft 25 rotates continuously under the operation of the motor 17, it will be evident that the bell cranks 143 and 144 will be continuously oscillating on 75

the bearings 125 and 126, respectively. Therefore, so long as the pawls 140 and 141 are allowed to cooperate with the teeth of the ratchet wheel 128, said wheel 139 and the paddle wheel 108 will be continuously revolved in a step-by-step manner. The two pawls 140 and 141 of unequal length are provided so that a movement of the bell cranks to rotate said pawls—a distance only half the displacement of the teeth of said ratchet 139 5 will be effective to rotate said ratchet wheel. That is, by providing the two pawls 140 and 141, a smaller arc of oscillation of the bell cranks 143 and 144 is required to rotate the ratchet wheel 139.

10 To provide for the selective operation of said ratchet wheel 139 and the consequent selective rotation of the refuse discharge paddle wheel 108 responsive to the operation of the float 53, the levers 130 and 131, which have an arcuate periphery, are provided with an arcuate shield 155 having an extension 156 which, in certain positions of adjustment, rides under the pawls 140 and 141 and prevents said pawls engaging the teeth of the ratchet wheel 139. Rigidly attached to said 15 levers 130 and 131 for rotation thereof about the bearing rings 132 and 133 is a bifurcated bracket 157 having a cross pin 158 adapted to move in the elongated slot 107 of the coupling 106. It is thus evident that the float 53 operating responsive to 20 the accumulation of refuse on the screen 36 will determine the position of the shield 155 with its extension 156 which will, in turn, determine whether or not the pawls 140 and 141, or either of said pawls, engage the teeth of the ratchet wheel 139 and will determine the extent of this 25 engagement.

25 The elongated opening 107 is provided so that the float 53 may have a limited up and down movement responsive to the pulsations of the 30 jiggling fluid passing through the screen 36, without affecting the shield 155. The limits of this movement may, of course, be varied by the position of the coupling 106 on the threaded end of the shaft 105.

30 It should be noted that the bell cranks 143 and 144 are pivoted on the stationary bearings 125 and 126, respectively; thus, there is no tendency for the shaft 109 to be oscillated responsive to the 35 continuous oscillation of the said bell cranks 143 and 144 except when there is engagement between one of the pawls 140 and 141 and the ratchet wheel 139 whereby the discharge of refuse will be completely under the control of the float mechanism. In addition, the washers 147 and 40 148 being also stationary and non-rotatably mounted on the bearings 125 and 126, respectively, there will be no tendency for the oscillatory movement of the bell cranks 143 and 144 to be transmitted to the brackets 130 and 131.

45 By virtue of the counter-balance weights 138 and 137, the mechanism comprising the levers 130 and 131 and all parts rigid therewith will remain in any position to which it is moved by the coupling 106 and thus will not tend to follow the normal 50 pulsating movement of this coupling. The position of the shield 155 will therefore be governed by the float mechanism and will not cause undue wear by needless continuous oscillation.

55 In the operation of the jig in the manner above described, it is evident that the refuse discharge mechanism of each of the compartments 12, 13 and 14 will operate responsively to the accumulation of refuse individual to each of said compartments. Shaft 25, common to all of said compartments, will maintain a constant oscillatory 55 movement of the bell cranks 143, 144 of each compartment. Floats 53 individual to each of said compartments will pulsate periodically under the influence of the pulsating movement of the jiggling fluid. This pulsating movement will not be transferred to the shield 155 of the discharge mechanism due to the lost motion connection provided by elongated slot 107. However, a predetermined maximum accumulation of refuse on any compartment screen 36 will alter the range of pulsating movement of coupling 106 and cause a rotation of shield 155 to remove its extension 156 to allow the pulsating movement of bell crank levers 143, 144 to be translated into rotary movement of paddle wheel 108 of discharge valve 40, through engagement of one of the pawls 140 or 141 with ratchet wheel 139. The refuse will thereby be discharged from chute 39 and screen 36 of the operating compartment until a predetermined minimum amount of refuse remains on said screen 36, which will result in extension 156 of shield 155 again lifting pawls 140 and 141 to prevent their engagement with ratchet wheel 139, responsive to the control of float 53. It is evident that the discharge of refuse is individual to each of the separate compartments 12, 13 and 14 and thus may be separately and differently adjusted, and the refuse on each bed 36 of each of said compartments may be maintained at any desired level within relatively narrow limits. 30

35 One of the features of our invention relates particularly to the construction of the refuse discharge chute 39. As best seen in Fig. 1, this chute includes as one wall thereof the pivoted member 160 which is pivotally supported adjacent the top thereof by pivot member 161 and which has a lower free end 162 of cylindrical configuration which free end is adapted to engage normally the paddle wheel 108. Said pivoted member 160 therefore normally guides the refuse 40 in the chute 39 to be discharged under the operation of the paddle wheel 108 of said refuse discharge valve 40. Should a large particle of material be received in said discharge chute 39 which might otherwise damage said refuse discharge 45 valve 40, the pivoted member 160 will pivot about its point 161, thereby yielding and preventing any damage to the refuse discharge valve 40. It is also to be noted that valve 40 is entirely below the screen 36. Chute 39 is therefore always filled 50 with refuse and a predetermined depth of refuse is maintained on said screen 36.

55 Another feature of our invention is the pivotal supporting means for the screens 36. The said screens 36 may take the form of a perforate plate 55 mounted upon a frame 163 comprising side and end angle members and both lateral and longitudinal reinforcing ribs, which are rigidly attached together and to said perforate plate, as by welding. Said frame also includes a downwardly extending plate 163' which is adapted to maintain sliding contact with the partition 43 during adjustment of said screen to confine the jiggling fluid of each sub-compartment to its screen portion. Adjacent its forward end, the screen is 60 supported on a pivot 164 for pivotal movement thereabout. The rear end of said screen 36 is adjustably supported from hangers 165 which depend from brackets on the side wall 32 and the partition 43. Said hangers 165 have nuts 166 adjacent the top thereof which may be adjusted to vary the height of the attached end of said screen 36. It is thus evident that the hangers 165 may be adjusted by the nuts 166 to pivot the screens 36 about the pivot 164 and thereby to vary the 75

inclination of said screens which will control the rate of travel of material thereacross.

Referring particularly to Figs. 10, 11 and 12, there is illustrated in detail a valve mechanism 44 which is particularly adapted to be employed with our invention as well as an eccentric mechanism 45, which is particularly adapted to be employed to operate said valve 44. Said valve 44 comprises a cylinder 259 provided in the upper 10 part thereof with a circumferential inlet port 260 comprising an annular opening communicating with a circumferential chamber 261 provided with a pipe fitting 262. Adjacent the lower part of said cylinder 259 is a plurality of discharge ports 263 communicating with atmospheric pressure. 15 In place of the discharge ports 263, there may be employed a continuous annular discharge port similar to the inlet port 260 and provided with a circumferential chamber therefor similar to the chamber 261. In this case, the circumferential chamber would be provided with one or more exhaust ports similar to the ports 263.

The bottom part of said cylinder 259 communicates with the bellied conduit 264 forming the 25 upper part of the air chamber 35. The upper part of the cylinder 259 is provided with a head 265 having an integral guide sleeve 266. Within the cylinder 259 is a pair of pistons 267 and 268. The piston 267 is adapted to control the opening 30 and closing of the inlet port 260 and the piston 268 is adapted to control the opening and closing of the discharge ports 263. The piston 267 is provided with a central hub 269 and axially extending spokes 270. The spokes 270 permit the 35 free movement of the air received through the inlet port 260, through the cylinder 259 to the conduit 264 and into the air chamber 35 when piston 267 is in inlet port opening position. The piston 268 is also provided with a hub 271 and 40 spokes 272 in order to allow the above mentioned free passage through the cylinder 259.

Rigidly attached to the hub 269 is a hollow sleeve 273 adapted to be guided in the guide sleeve 266. The upper end of said hollow sleeve 273 is 45 screw threaded, as illustrated at 274, and is adapted to receive screw-threadedly a split guide thimble 275 which may be clamped rigidly thereto after having been adjusted to a desired position with respect to the threaded neck portion 271 of said guide thimble 275. The inner cylindrical surface of said guide thimble 275 is adapted to slide on the outer surface of the guide sleeve 266. A U-shaped link 278, carrying a connecting rod 242, is pivoted to laterally extending lugs 280, 280 55 of the thimble 275.

Projecting through the longitudinal opening 281 of the hollow sleeve 273 is a shaft 282 rigidly attached at its lower end with the hub 271 of the piston 268 and adjustably connected to the hollow sleeve 273 at its upper end by screw threads 283. A clamping nut 284 is provided for clamping said shaft 282 rigidly with said hollow sleeve 273 after the former is adjusted to a desired position. To provide for the adjustment of said shaft 282 with 60 respect to said hollow sleeve 273, the top of said shaft 282 is preferably squared as indicated at 285, whereby a wrench may be employed to rotate said shaft 282 and thereby effect its adjustment. The portion 279 of sleeve 273 is also 65 squared to receive a tool whereby it may be prevented from turning with shaft 282 during adjustment of said shaft. As the piston 267 is rigidly attached to the hollow sleeve 273 and as the piston 268 is rigidly attached to the shaft 282, it 70 is obvious that by rotating said shaft 282, which

is screw-threaded at 283, with said hollow sleeve 273, the position of the piston 268 may be adjusted with respect to the piston 267. This adjustment may be made within wide limits and, when any desired adjustment is effected, it may 5 be maintained by clamping home the clamp nut 284. After said adjustment is made between said pistons 267 and 268, said pistons are adapted to be moved in unison under the control of the connecting rod 242. By virtue of the adjustability 10 afforded by the screw-threaded connection between the threaded portion 274 of the hollow sleeve 273 and the cooperating threaded portion of the guide thimble 275, said guide thimble 275 may be adjusted with respect to said hollow sleeve 15 273 and thus the positions of said pistons 267 and 268 may be adjusted with respect to the connecting rod 242. The upper end of the connecting rod 242 is connected to an eccentric mechanism 45.

There is also illustrated in Figs. 10, 11 and 12 a particular type of adjustable eccentric mechanism which is particularly well adapted for use as an element of our invention. Said eccentric mechanism comprises a split strap 286 rigidly connected with the connecting rod 242. Mounted upon the shaft 20 for rotation therewith is a bushing 288 provided with a circumferential flange 289 and a cylindrical hub 290. This mounting is effected by the usual keyway in the shaft 20 with 30 which cooperates a key 288' against which is adapted to impinge a set screw 289' threaded through said bushing 288. It may be stated that the keyways on shafts 20 and 21 are all preferably formed in longitudinal alignment. Said hub 35 290 is adapted to fit into an oval-shaped opening 291 having parallel side walls in an eccentric plate 292, which plate is rotatably mounted between side flanges of the strap 286 and is carried between the flange 289 and a retaining washer 293, bolted to said bushing 288, as by cap screws 293'. The stroke of the connecting rod 242 is, of course, controlled by the spacing between the axis of rotation of the eccentric plate 292 or 40 the center thereof, and the axis of rotation of the shaft 20; that is, the stroke will be twice this spacing. In order to control variably the stroke of said connecting rod 242, the eccentric plate 292 is made adjustable with respect to the bushing 288 whereby said axial spacing may be controlled 45 at will. The oval-shaped opening 291 permits relative adjustment between the eccentric plate 292 and said bushing 288. To effect this adjustment and also to effect a further adjustment which will be discussed more in detail hereinafter, 50 the flange 289 is provided with three angularly positioned conical holes 295' adapted to receive selectively the frusto-conical head 295 of a pin 294, the axis of rotation of which head is spaced with respect to the axis of rotation of said pin 294. Said pin 294 is adapted to be received in a drill 55 hole in the plate 292. The axial extension of said frusto-conical head 295 is screw-threaded to receive a nut 296 and at its extremity is squared at 297 to receive a tool. By virtue of this adjusting device, the position of the eccentric plate 292, with respect to the bushing 288, may be adjustably determined and fixed in a determined position. This is accomplished by placing the head 295 in one of the three angularly spaced 60 holes 295' and rotating the pin 294 about its axis of rotation to move the hub 290 of the bushing 288 to any desired position in the oval shaped opening 291 where it may be held by clamping home the nut 296. The retaining washer 293 is 65 70 75 80 85 90 95 100

also effective to maintain this adjustment when clamped by cap screws 293'.

As illustrated in Fig. 12, the distance between the outer wall of the hub 290 within the oval-shaped opening 291 and the wall defining said opening 291 may be adjusted by the rotation of the pin 294 about its axis. This may be effected by a wrench fitted on the square head 297. Along the section line illustrated in Fig. 12, the said walls are spaced at substantially their maximum distance. By rotating the pin 294, the axis of rotation of the frusto-conical head 295 will be moved upwardly and will decrease the mentioned distance. This affords the above mentioned adjustment of the length of the stroke of the connecting rod 242. In addition to the above mentioned adjustment, by removing the retaining washer 293 and the nut 296, it is possible to move the eccentric plate 292 along with the pin 294, having a frusto-conical head 295, in axial direction sufficiently to disengage the head 295 from the conical hole 295' in which it is positioned and to rotate the eccentric plate 292 either 120 or 240 degrees in either direction and then place said head 295 in another of said conical holes 295'; that is, plate 292 may have any one of three angular positions relative to the bushing 288. By this expedient, a plurality of valves may be driven from the common shaft 20 and their cycle of operation may be either 120 or 240 degrees in phase relation. In addition, the cycle of operation of any one valve may be adjusted in phase relation either 120 or 240 degrees from any prior setting thereof.

35 By employing the adjustable eccentric mechanism and the adjustable dual piston valve mechanism illustrated in Figs. 10, 11 and 12, very flexible control of the admission of air under pressure to the discharge chambers 35, the maintenance of air in said chambers and the discharge of air therefrom is provided. The adjustable eccentric mechanism 45 provides for an adjustable stroke of the connecting rod 242 and a resulting adjustable stroke for the pistons 267 and 268. Said adjustable eccentric mechanism 45 also provides for adjusting the phase relation between two or more valves. The adjustable thimble 275 provides for an adjustable determination of the limits within which said pistons 267 and 268 will operate for any given eccentric adjustment and any given relative adjustment of pistons 267 and 268; and the adjustment provided between the shaft 282 and the hollow sleeve 273 provides an adjustment for the relative positions of the pistons 267 and 268 which, in turn, provides for the relative times of opening and closing of the inlet port 260 and the discharge ports 263. With the valve 44 and the eccentric mechanism 45 adjusted as illustrated in Figs. 10, 11 and 12 and with the shaft 20 rotating in a counter-clockwise direction as viewed in Fig. 10, a cycle of operation of the device will be substantially as follows: With the valve 44 in the position illustrated in Fig. 11, both the inlet port 260 and the discharge ports 263 are closed and the chamber 35 is sealed at an initial atmospheric pressure following a period of exhaustion of chamber 35. As the shaft 20 rotates counter-clockwise and 70 the pistons 267 and 268 are moved downwardly, the inlet port 260 is opened as the eccentric device 45 approaches the lower limit of its stroke. The discharge ports 263 are maintained closed through this portion of the cycle. It may be noted that, as the inlet port 260 does not begin

to open until the eccentric 45 has approached the downward extremity of its stroke, the rate of opening of said port 260 will be small in comparison with what it would have been had said port started to open at approximately the instant the axis of the eccentric plate 292 passed below the axis of the shaft 20. With the connecting rod 242 in its extreme downward position of the stroke, the inlet port 260 will be completely opened and the discharge ports 263 will be closed. As soon as inlet port 260 starts to open, air under pressure will be admitted to the chamber 35 to produce upward movement of the jiggling fluid through the screen 36. On return movement of the connecting rod 242 under the control of the eccentric 45, the inlet port 260 will be closed while the outlet ports 263 will be maintained closed. Under these conditions, the chamber 35 is effectively sealed under initial pressure above atmospheric pressure and this condition is maintained until the connecting rod 242 has substantially completed its stroke in the upward direction under the control of the eccentric mechanism 45. When the connecting rod 242 substantially completes its upward stroke, said discharge ports 263 are opened while the inlet port 260 is maintained closed and the chamber 35 is free to exhaust at atmospheric pressure. During the following downward movement of pistons 267 and 268, exhaust ports 263 will be closed while inlet port 260 is maintained closed and the chamber 35 is effectively sealed under conditions of initial atmospheric pressure. This completes a cycle of operation of the said mechanism.

35 The period during which the inlet port 260 is opened and fluid under pressure is admitted to the air chamber 35 is designated the inlet period. The following period during which ports 260 and 263 are both closed under conditions of initial pressure above atmospheric, is designated the expansion period. The following period during which exhaust ports 263 are opened is designated the exhaust period and the final period during which ports 260 and 263 are closed under initial atmospheric pressure is designated the compression period.

40 It may be noted that with this particular valve construction the expansion and compression periods are, of necessity, of relatively equal duration of time while the inlet and exhaust periods may be varied within wide limits and may be of different time durations.

45 By lowering the position of the piston 267 with respect to the connecting rod 242, the period during which the inlet port 260 is maintained open may be increased and, by raising said piston with respect to said connecting rod, said period may be reduced. This period may be varied between wide limits from 20 degrees to 60 300 degrees of movement of shaft 20, by controlling the position of said piston 267 on said hollow sleeve 273. Likewise, by lowering the position of the piston 268 with respect to the connecting rod 242, the period during which the discharge ports 263 are open may be reduced and, by raising this piston with respect to said connecting rod, said period may be increased. This period may also be varied between the limits above mentioned for piston 267. It is to be noted that the length of the piston 267 is such that under no condition may said piston be moved upwardly sufficiently to open the inlet port 260. This requires the opening of said inlet port 260 to take place only during the down- 70 75

ward movement of the connecting rod 242. The piston 268 is also of such length and is preferably so adjusted that under no condition will the discharge port 263 be opened responsive to a 5 downward movement of the connecting rod 242. That is, inlet port 260, under the control of the piston 267, is adapted to be opened only in response to a downward movement of the connecting rod 242 and the discharge ports 263, under 10 the control of the piston 268, are adapted to be opened only in response to an upward movement of the connecting rod 242. Furthermore, the pistons 267 and 268 are preferably so adjusted that under no condition will ports 260 and 263 15 be open at the same time for, if this condition exists, the air under pressure will enter the cylinder 259 through inlet port 260 and be discharged to the atmosphere through the discharge ports 263, thereby wasting the air and 20 doing no useful work. It is obvious that the portion of any cycle of operation, during which inlet port 260 may be opened and discharge ports 263 closed, may be varied within wide limits and the portion of the cycle, during which discharge 25 ports 263 may be opened and inlet port 260 closed, may likewise be varied within wide limits. In addition, the condition under which both the inlet port 260 and the discharge ports 263 are closed may be varied within wide limits and, in 30 fact, this period may be reduced to substantially zero or increased to substantially 150 degrees. It may be noted, however, that with this particular valve construction, this period cannot exceed even theoretically 180 degrees and as a practical 35 matter the limit is about 150 degrees.

In addition, the rate at which ports 260 and 40 263 are opened and closed once their respective pistons begin an opening and closing operation may be varied by varying the stroke of the connecting rod 242 and by varying the instant 45 during any cycle of operation at which said opening or closing operation begins. The latter factor is, of course, determined to a large extent by the portion of the cycle a valve is adjusted to be opened while the former is independently adjustable. For example, if the portion of any cycle defining the limits during which port 260 first starts to open until it is totally closed is small, such as 60 degrees, then it will begin to 50 open when eccentric 45 approaches the lower part of its stroke during which the rate of movement of piston 267 is relatively small. On the other hand, if the portion of the cycle defining the limits during which ports 260 first starts to open until it is totally closed is 180 degrees, then it begins to open when eccentric 45 is midway of its downward stroke. At this portion of its movement, the piston 267 is moving at its maximum velocity. It is, of course, evident that 55 the rate of opening and the rate of closing of either of the ports 260 or 263 will be the same though the rate of opening and closing of the inlet port 260 may be different from that of the discharge ports 263.

60 It is thus obvious that with the eccentric operated valve structure illustrated in Figs. 10, 11 and 12, the period during which the fluid is admitted to the chambers 35, the rate of this admission, the period during which the discharge 65 ports 263 are closed and the rate of opening thereof may be varied within wide limits, thus providing a very flexible means for controlling the cyclic movement of the jiggling fluid with respect to the screen 36.

70 A cycle of operation of the jiggling fluid under

the influence of the cyclically operating valve 44 in a typical case will be substantially as follows: During the air inlet period, the jiggling fluid will move upwardly through the screen 36. During the expansion period which follows, the jiggling fluid will continue to move upwardly through said screen 36 though at a decreasing velocity. It may be that said upward movement will continue beyond the expansion period and for a short interval into the following exhaust period, 10 and it is even possible that said upward movement may terminate prior to the termination of the expansion period. During the exhaust period, the upward movement of the fluid is terminated, unless previously terminated and for 15 an instant said fluid is at rest. Following this instant of rest, the fluid moves downwardly through the screen 36 at an increasing rate of 20 downward velocity. This increasing downward velocity is ordinarily checked before the end of the exhaust period and the downward velocity is maintained at a sharper reduced rate during 25 the latter part of the exhaust period. During the following compression period, the air in the chamber 35 is compressed by the downward movement of the fluid through the screen 36, which compressed air is effective to reduce the downward velocity of said fluid to zero. In some cases, it has actually been found that during the compression period the air is sufficiently compressed to reduce not only the downward velocity of the fluid to zero but to start the upward velocity of the fluid with respect to the screen 30 35 just prior to the beginning of the following air inlet period. Under certain adjustments of the valve, it has also been found that the compression period is not quite sufficient to reduce said downward velocity to zero and this is accomplished by the first part of the following inlet period.

40 It is evident that the device comprising our invention is very flexible and each of the several compartments 12, 13 and 14 may be independently adjusted by virtue of a large number of independently adjustable means to take care of the particular problem presented to each of said compartments. For example, the inclination of the screen of each of said compartments may be separately and individually adjusted. The rate of discharge of the accumulated refuse on each 45 of the screens 36 may be independently adjusted and the allowed depth of refuse bed or amount of accumulated refuse may be independently adjusted for each compartment. The size of the refuse discharge opening and the height of the 50 weir of each compartment may be separately adjusted. In addition, each of said compartments is divided into two sub-compartments 55 each sub-compartment of which has an individual periodically operated air control valve for controlling the pulsations of the jiggling fluid in that sub-compartment. Each of said sub-compartments also has an individual source of water supply and an individually controllable fluid guide plate for directing the jiggling fluid 60 to that portion of the screen 36 positioned above said sub-compartment.

65 In addition, the phase relation of the valves individual to each of the compartments 12, 13 and 14 may be adjusted within wide ranges. As 70 above suggested, each group of said valves individual to the several compartments 12, 13 and 14 may be set 120 degrees out of phase. This particular setting is, of course, by no means necessary and, if desired, all of said valves may be 75

operated in phase or four of said valves may be operated in phase while two of said valves which, for example, are individual to one of the compartments, may operate out of phase there-
 5 with by any desired amount. Furthermore, if desired, one valve individual to each of the compartments may be set 120 degrees out of phase, with the valves of any one compartment also set 120 degrees out of phase. However, the pre-
 10 ferred setting is with the valves of the several compartments 120 degrees out of phase. This reduces to a minimum the amount of air drawn from the tank 47 at any instant. By virtue of this feature, the pressure in said tank 47 may be
 15 maintained substantially constant with a relatively small pump or blower 46. Furthermore, due to this constancy of pressure in tank 47, the operation of the jig is more uniform and efficient. This is due to the fact that a constant air
 20 pressure is always available and the resulting operation may be more accurately controlled by valves 44. Full pressure is always available at the end of a stroke as well as at the start thereof and, should there be any overlapping of
 25 the air inlet periods of two compartments, the second compartment would have available the full air pressure, which is necessary for its proper action.

In the operation of our device, a very efficient
 30 jigging of material—as, for example, coal—may be realized due to the above mentioned extreme flexibility of the adjustments of each of the compartments 12, 13 and 14. In addition to the elements described above in detail, it may be
 35 mentioned that the drive mechanisms 26 and 27 are each provided with a chain tensioning mechanism which may take the form of a pivoted bell crank having a roller on one arm thereof adapted to ride on the chain and an adjustable weight
 40 on the other arm thereof. These devices are clearly seen in Fig. 2 of the drawings.

The device of our invention may be employed to perform substantially any desired cycle of jigging operation and it is particularly adapted to
 45 operate in accordance with the method of jigging disclosed in the above mentioned application of Byron M. Bird, Serial No. 737,443, though it is obviously not restricted to this particular method of jigging.

50 The steps involved in said method are described generally in the above description of the operation of valve 44. It may be further pointed out that the cycle of operation of each compartment involves the upward movement of fluid
 55 through the screen 36, first at a relatively slow rate to open the top of the bed, followed by an increased rate which lifts the entire bed as a mass. The bed then opens rather rapidly throughout, after which the fluid continues its
 60 upward movement but at a rapidly decreasing rate. This is followed by downward movement of the fluid through screen 36 which is cushioned by the air trapped in air chamber 35 during the compression period and brought to rest thereby.
 65 The stratification of the material takes place while the bed is open. This particular method of jigging has been found to provide a more complete separation of materials according to specific gravity and to be capable of treating a
 70 wider size range of materials than has heretofore been satisfactorily treated.

Obviously those skilled in the art may make various changes in the details and arrangement of parts without departing from the spirit and
 75 scope of the invention as defined by the claims

hereto appended, and we wish therefore not to be restricted to the precise construction herein disclosed.

Having thus described and shown an embodiment of our invention, what we desire to secure 5 by Letters Patent of the United States is:

1. In a jig, the combination with a tank adapted to contain a jigging fluid, of a pivoted deflecting plate in said tank, said plate having a pivotal connection adjacent the top of said plate 10 extending substantially parallel with a side wall of said tank, an adjusting rod attached to the lower end of said plate and extending through a side wall of said tank, and combined adjusting and packing means cooperating with said rod 15 where it extends through said wall to adjust pivotally said plate and provide a fluid-tight packing for said rod.

2. In a jig, the combination with a device comprising a plurality of sections each of which 20 comprises a fluid container, a material supporting screen and a refuse discharge valve, of operating means common to all of said refuse discharge valves, and refuse accumulation controlled means individual to each section for effecting operative connection between the refuse discharge valve of said section and said common operating means, said refuse controlled means comprising a float having a rounded front and tapering sides leading to a relatively sharp rear 30

3. In a jig, the combination with a tank, of a screen in said tank, means for causing periodic upward movement of jigging fluid through said screen to stratify material thereon, float mechanism 35 for determining the depth of refuse on said screen, said mechanism comprising an elongated upright float having a rounded front and tapering side walls leading to a sharp rear portion, means for pivotally mounting said float including lever arms, one on each side of said float, each having a plurality of vertically spaced holes adapted to receive selectively a cross pin for connecting said float to said arms, a variable counter-weight for adjusting the buoyancy of 45 said float, a refuse valve controlling lever operatively connected to said float, and means for varying the leverage of said float thereon.

4. In a jig, the combination with a tank, of a screen in said tank, means for causing periodic upward movement of jigging fluid through said screen to stratify material thereon, float mechanism 50 for determining the depth of refuse on said screen, said mechanism comprising an elongated upright float having a rounded front and tapering side walls leading to a sharp rear portion, and means operated by said float mechanism 55 for controlling the discharge of refuse accumulated on said screen.

5. In a jig, the combination with a tank adapted to contain a jigging fluid, of an adjustable screen within said tank, a partition dividing said tank into a plurality of sub-compartments to which said screen is common, means individual to each sub-compartment for causing jigging fluid to move cyclically through said screen, and means comprising an extension on the bottom of said screen to provide a continuation of said partition to said screen for varying positions of said screen.

6. In a jig, the combination with a tank having upright longitudinally extending side walls and end walls, of an upright longitudinally extending partition positioned between said side walls and dividing said tank into two compart- 75

- ments, a perforate material supporting screen in one of said compartments through which jigging fluid is adapted to be moved, means associated with the other compartment for periodically forcing said fluid through said screen, said longitudinally extending partition comprising an upper stationary portion adapted to aid in supporting said screen and a lowermost portion which is pivoted at its top at the lower extremity 5 of said upper stationary portion, wiper means carried on the ends of said lowermost partition adapted to wipe the end walls of said tank, and means for adjusting said pivoted portion about its pivot.
- 10 7. In a jig, the combination with a tank, of a screen in said tank, means for causing periodic upward movement of jigging fluid through said screen to stratify material thereon, float mechanism for determining the depth of refuse on said screen, said mechanism comprising a float having a rounded front and tapering sides leading to a relatively sharp rear portion, and means operated by said float mechanism for controlling the discharge of refuse accumulated on said 15 screen.
- 20 8. In a jig, the combination with a tank, of a material supporting screen therein, means for causing jigging liquid to move upwardly periodically through said screen to stratify material thereon containing refuse, a refuse ejecting rotary valve, an oscillating arm for rotating said valve, a float constructed and arranged to determine the depth of stratified refuse on said screen, and means controlled by said float and constructed and arranged to cause said rotary valve 25 to rotate through a variable angle for each oscillation of said oscillating arm, said angle depending upon the position of said float as determined by the depth of refuse on said screen.
- 30 9. In a jig, the combination with a tank, of a coal supporting screen therein, means of causing jigging liquid to move upwardly periodically through said screen to stratify the coal thereon into layers of refuse and clean coal, a rotary 35 refuse ejector, a reciprocating member for im-
- parting rotary movement to said valve, a pivoted float constructed and arranged to determine the depth of said refuse bed, anti-friction mountings for said float, and mechanism controlled by said float and cooperating with said reciprocating member to determine variably the extent of rotation of said ejector for each reciprocation of said member as determined by the depth of said refuse bed.
- 40 10. In a jig, the combination with a tank, of a coal supporting screen therein, means for causing jigging liquid to move upwardly periodically through said screen to stratify the coal thereon into layers of refuse and clean coal, a rotary 45 refuse ejector, oscillating means for rotating said ejector in steps, and means including a refuse responsive float for controlling variably the angle of rotation of said ejector for each oscillation of said oscillating means, as determined by the depth of the refuse on said screen.
- 50 11. In a jig, the combination with a tank, of a coal supporting screen therein, means for causing jigging liquid to move upwardly periodically through said screen to stratify the coal thereon into layers of refuse and clean coal, a rotary 55 refuse ejector, oscillating means for rotating said ejector in steps, and means for controlling variably the angle of rotation of said ejector for each oscillation of said oscillating means, as determined by the depth of the refuse on said screen.
- 60 12. In a jig, the combination with a tank, adapted to contain a jigging fluid, of an adjustable screen within said tank, a partition dividing said tank into a plurality of sub-compartments to which said screen is common, means individual to each sub-compartment for causing jigging fluid to move cyclically through said screen, and means constructed and arranged to provide a continuation of said partition to said screen for varying positions of said screen thereby isolating said sub-compartments below said screen regardless of its positions of adjustment.
